UNITED STATES PATENT OFFICE.

JORDAN E. STORMS, OF JACKSONVILLE, FLORIDA, ASSIGNOR OF ONE-HALF TO THE ARTHUR-JOCELYN SALES COMPANY, OF JACKSONVILLE, FLORIDA, A PARTNERSHIP COMPOSED OF THEODORE A. BLINN, WILLIAM H. MELRATH, AND R. JOCELYN GOFF.

DIAPHRAGM-HORN.

1,365,563.

Specification of Letters Patent. Patented Jan. 11, 1921.

Application filed July 10, 1916. Serial No. 108,444.

To all whom it may concern:

Be it known that I, JORDAN E. STORMS, a citizen of the United States, residing at Jacksonville, in the county of Duval and

5 State of Florida, have invented new and useful Improvements in Diaphragm-Horns, of which the following is a specification.

This invention relates to improvements in diaphragm horns such as are used for alarm 10 or warning signal purposes, principally upon motor vehicles.

The principal objects of the invention, briefly stated, are to provide a horn wherein the diaphragm may be vibrated at a relatively 15 high frequency and through a maximum extent in order to produce sound waves of great length and sounds of musical pitch and to cause the bell and the air column therein to become resonant; to provide a horn wherein the diaphragm although 20 vibrating at high frequency will not have any uncontrolled reactionary vibrations but will be at all times completely under the control of its actuating element in order to enable the pitch, intensity and character of 25 the sound or note produced to be definitely predetermined in connection with the construction or patterning of the said element; to provide a horn wherein the diaphragm 30 actuating element may be readily replaced, whenever desired, by another one having a different pattern and which will produce a note or sound of different pitch, intensity, or character; and to provide a horn wherein 35 the operative relation between the diaphragm and its actuating element will not be affected by the vibration of the vehicle on which the horn may be carried.

The invention consists in certain novel 40 features of construction, combination and relation which together with the above and other objects and advantages will appear as the description proceeds.

A preferred embodiment of the invention 45 is illustrated in the accompanying drawings wherein:

Figure 1 is a perspective view of a horn in which the features of the invention are incorporated.

50 Fig. 2 is a side elevation, the casing cover plate being removed.

Fig. 3 is a vertical cross section on the line 3—3 of Fig. 2.

Fig. 4 is a detail vertical sectional view

showing the relation between the diaphragm and its actuating element.

Fig. 5 is a detail elevation of the diaphragm.

Figs. 6 and 7 are, respectively, a detail plan and side elevation of the blank from which the stylus holder is formed.

Fig. 8 is a detail elevation of the stylus holder, showing, in section, the relation between it and the diaphragm.

Fig. 9 is a detail plan view of the stylus.

Fig. 10 is a plan and Fig. 11 is a side elevation of the diaphragm actuating element.

Fig. 12 is a fragmentary side elevation of a gear wheel which in the present embodiment, constitutes a carrier for the diaphragm actuating element.

Fig. 13 is a detail view showing in disassembled relation certain parts which serve for the mounting and electrical connection of a binding post.

Fig. 14 is a front elevation of the casing which incloses the operating parts.

Fig. 15 is a front elevation of the sound chamber, and

Fig. 16 is a detail sectional view on the line 16—16 of Fig. 2.

Similar characters of reference designate corresponding parts throughout the several views.

The operating parts are inclosed in a casing 1 which has as one of its side walls a removable cover plate 2. The casing 1 has at its front end an extension 3 terminating in a disk-like flange 4 to which is secured a casting 5. The casting 5 is interiorly fashioned to provide a sound chamber 6 and has a central tubular or cylindrical nipple 7 upon which is mounted a bell or resonator 8 of the usual flaring form.

The plate 2 is secured to the casing 1 by fastening screws 9, one of which is threaded into the extension 3 and the others of which are threaded into lugs 10 arranged internally of said casing and by a screw 11 passed through the top wall of the casing and threaded into a lug 12 projecting laterally from the plate 2. Upon the removal of the screws 9 and 11 the plate 2 may be removed from the casing to enable free access to the parts, as will be apparent from Fig. 2.

The casting 5 has as a part thereof an annular attachment flange 13 which is posi-

tioned against the flange 4 and secured thereto by screw and nut fastenings 14. The two lower fastenings 14 are also utilized to connect the casing to one of the upright arms of a U-shaped bracket 15 whose other arm is secured to the opposite end of the casing by screws 16. The bracket is employed to secure the horn to a suitable supporting element.

- 10 The horn is sounded by the rapid vibration of a resilient diaphragm or plate 17 which extends across the sound chamber 6, forming a base therefor, and has its marginal portion secured between gaskets 18 fitted in annular recesses formed internally of the casting 5.
- 15 The actuating means for the diaphragm comprises an actuating element 19 and a stylus 20 co-acting with said element and whose vibrations are transmitted to the diaphragm.

20 The stylus 20 is mounted in a holder 21 fashioned from the blank shown in Figs. 6 and 7. The holder 21 has at its upper end a bearing ring 22 which fits squarely against the rear face of the diaphragm 17 and is provided with a central projection 23 passing through a central opening 24 of the diaphragm. The projection 23 carries adjacent the front face of the diaphragm a suitably secured retaining washer 25 and provides a pivotal connection between the diaphragm and the holder 21 whereby the latter may have slight lateral play under certain conditions. The holder 21 has a resilient shank 26 which extends rearward and downward from the ring 22 and is formed with a horizontally disposed clamp or socket 27 in which the stylus is securely held.

25 The actuating element 19 is preferably, and as shown, in the form of a ring. Said element has a peripheral groove 28 of pronounced depth in which the stylus is held and operates. The surface of the groove 28 is patterned to produce such vibrations of the stylus as will cause a sound or note of definite pitch, intensity, and character. It is obvious that the sound produced depends on the depth, frequency, outline and relation of the alternating projections 29 and 30 transverse grooves 29 which make up the pattern of the groove 28 and that sounds of different character may be produced at will by suitable selections of the pattern of the groove 28. In the embodiment shown the 35 actuating element has two differently patterned grooves 28 in parallel planes, either of which may be used to operate the stylus accordingly as said element is in one position or the other.

40 The ring 19 is fitted upon a rotatable drum 30 whose shaft 31 has its bearings in the permanent side wall of the casing 1 and in the cover plate 2. The drum 30 has at one side thereof a circumscribing flange 32 against 45 which the ring 19 is positioned; and said

ring is held against lateral displacement from said drum by said flange and also by retaining screws 33 which are threaded into lugs or sockets 34 formed with the spokes connecting the drum and its shaft 31. The ring 19 is held against peripheral displacement on the drum 30 by lugs or projections 35 formed with said drum and engaging in recesses 36 in the inner circumferential face of said ring. Where the ring 19 has two grooves 28 as shown, the recesses 36 are provided at each side of said ring. Obviously, by removing the screws 33 the ring may be removed from the drum and placed in reverse position thereon in case it may be desired to change from one groove 28 to the other in connection with the actuation of the stylus; or another ring having a groove or grooves of different pattern may be substituted. Before removing or replacing the ring 19, the screws 14 are first loosened to some extent to enable the diaphragm and therewith the stylus 20 to be pulled forward in order that said stylus may be out of the way of the ring. When the ring 19 has been fitted on the drum the screws 14 are tightened and the stylus is thus brought into the groove 28. This avoids springing the holder 21 in connection with the assemblage or disassembly of the ring 19.

45 The drum 30 and therewith the ring 19 are preferably motor actuated and are driven from the motor shaft by suitable reducing gearing. The rear portions of the casing 1 and plate 2 are formed to inclose an electric motor 37 whose base is secured by screw and nut fastenings to the base of the casing 1. The terminal wires 38 are connected to binding posts 39 mounted externally of the casing by screws 40 threaded into said binding posts and passing through washers 41 which insulate the binding posts and screws 40 from the casing.

50 The gearing for driving the drum 30 includes a pinion 42 mounted on the motor shaft, an internal gear 43 formed with the drum 30 and co-axial rigidly connected large and small pinions 44 and 45. The pinion 44 is larger than the pinion 42 by which it is driven and the pinion 45 is smaller than the gear 43 which it drives. The pinions 44 and 45 are rotatably mounted on a common supporting stem 46 which is fitted in an opening in the permanent side wall of the casing and whose outer end is secured by an externally arranged nut 47.

55 The diaphragm 17 when in its normal position is in a plane and in such position that the stylus 20 bears with considerable pressure against the surface of the groove 28. The stylus follows the pattern of the groove owing to the resiliency of the diaphragm and of the holder 21 and effects vibrations of the diaphragm in exact accordance with the pattern of the ring 19, the relation being 60

such that the vibrations of the diaphragm are completely under the control of the said ring, notwithstanding the tendency of the diaphragm to assume its normal plane.

- 5 The horn may be operated to give forth sound for long or short periods or at varying intervals as may be desired by suitably controlling the operation of the motor 37. When the pattern of the ring 19 is selected 10 to provide for a sound having a characteristic irregularity, *e. g.* a sound of rising and falling pitch or of increasing and diminishing intensity, this sound will be continuously repeated throughout a continuous rotation of the ring 19 through several revolutions.

While I have described a single preferred embodiment of the invention, it will be understood that this description when taken in 20 connection with the appended claims is not intended to limit the scope which they may have by virtue of their terms or to be taken otherwise than for purposes of exposition or interpretation.

25 Having thus described my invention, what I claim is:—

1. In a horn, the combination of a resili- 30 ent, vibratory diaphragm, a stylus connected therewith; and a movable diaphragm- actuating element having a groove with a plurality of spaced projections therein to produce a definitely-patterned surface against which the stylus is constantly pressed by the diaphragm, whereby said diaphragm is 35 maintained at all times under the direct control of said actuating element; said patterned surface being designed to vibrate said diaphragm, by means of the stylus, at a high frequency, so as to originate a sus- 40 tained musical sound of definite pitch and intensity.

2. In a horn, the combination of a resili- 45 ent, vibratory diaphragm, a stylus connected therewith; and a rotatable diaphragm- actuating ring having a peripheral groove with a plurality of spaced projections therein to produce a definitely-patterned surface against which the stylus is constantly pressed by the diaphragm, whereby said 50 diaphragm is maintained at all times under the direct control of said actuating element; said patterned surface being designed to vibrate said diaphragm, by means of the stylus, at a high frequency, so as to origi- 55 nate a sustained musical sound of definite pitch and intensity.

3. In a horn, the combination of a resili- 60 ent, vibratory diaphragm, a stylus connected therewith; and a movable diaphragm-act- 65 tuating element having a relatively-deep, peripheral groove with a plurality of alined spaced projections therein to produce a surface of a definite pattern, against which the stylus is constantly pressed by the dia- phragm, whereby said diaphragm is main-

tained at all times under the direct control of said actuating element; said patterned surface being designed to vibrate said dia- phragm, by means of the stylus, at a high frequency, so as to originate a sustained 70 musical sound of definite pitch and intensity.

4. In a horn, the combination of a resili- 75 ent, vibratory diaphragm; a stylus connected therewith; a resonator projecting from said diaphragm; and a movable dia- phragm-actuating element having a groove with a plurality of projections and intersecting grooves of different dimensions therein to produce a definitely-patterned sur- 80 face against which the stylus is constantly pressed by the diaphragm, whereby said diaphragm is maintained at all times under the direct control of said actuating element; said patterned surface being designed 85 to vibrate said diaphragm, by means of the stylus, at a high frequency, and through a maximum extent, so as to originate a sus- tained musical sound of definite pitch and intensity and to set up air-column resonance 90 in the resonator.

5. In a horn, the combination of a resili- 95 ent, vibratory diaphragm; a stylus connected therewith; a resonator projecting from said diaphragm; and a rotatable diaphragm- actuating ring having an endless groove with a plurality of alternately arranged projections and intersecting grooves to produce a definitely-patterned surface against which the stylus is constantly pressed by 100 the diaphragm, whereby said diaphragm is maintained at all times under the direct control of said ring; said patterned surface being designed to vibrate said diaphragm, by means of the stylus, at a high frequency, 105 and through a maximum extent, so as to originate a sustained musical sound of definite pitch and intensity and to set up air- column resonance in the resonator.

6. In a horn, the combination of a resili- 110 ent, vibratory diaphragm; a stylus connected therewith; a rotatable diaphragm-actu- 115 ating ring having a plurality of alternately arranged projections and transverse intersecting grooves to produce a definitely-pat- terned surface against which the stylus is constantly pressed by the diaphragm, where- 120 by said diaphragm is maintained at all times under the direct control of said ring; said patterned surface being designed to vibrate said diaphragm, by means of the stylus, at a high frequency, so as to origi- 125 nate a sustained musical sound of definite pitch and intensity; and a rotatable carrier upon which said ring is removably mounted.

7. In a horn, the combination of a resili- 130 ent vibratory diaphragm, a stylus associated therewith, a rotatable diaphragm actu- ating ring being formed with two parallel endless grooves arranged side by side and

4

having definitely patterned surfaces against one or the other of which the stylus is constantly pressed by the diaphragm; the patterned surface of each groove consisting of 5 a plurality of alternately arranged projections and intersecting transverse grooves; and the patterned surfaces in the two grooves differing from each other and each designed to vibrate the diaphragm 10 through the medium of the stylus at a high frequency so as to originate a different musical sound of definite pitch and intensity, the said ring being shiftable laterally to bring either of the patterned surfaces thereof into 15 position for co-action with said stylus.

8. In a horn, the combination of a resili-
ent, vibratory diaphragm; a stylus connect-
ed therewith; and a rotatable diaphragm-
actuating ring formed with two parallel,
20 endless grooves arranged side by side and

having definitely patterned surfaces against one or the other of which the stylus is constantly pressed by the diaphragm; whereby said diaphragm is maintained at all times under the direct control of said ring; said 25 patterned surfaces being different from each other and each designed to vibrate said dia- phragm, by means of said stylus, at a high frequency, so as to originate a different musical sound of definite pitch and inten- 30 sity; and said ring being shiftable laterally to bring either of said surfaces into position for co-action with said stylus.

In testimony whereof I have hereunto set my hand in presence of two subscribing wit- 35 nesses.
